UNITED STATES PATENT OFFICE.

JOSEPH W. GOTOBED AND ROSCOE F. FORWARD, OF VILLISCA, IOWA.

DOOR-OPERATING MECHANISM.

1,216,439.

Specification of Letters Patent. Patented Feb. 20, 1917.

Application filed March 27, 1916. Serial No. 87,076.

To all whom it may concern:

Be it known that we, JOSEPH W. GOTOBED and ROSCOE F. FORWARD, citizens of the United States, residing at Villisca, in the county of Montgomery and State of Iowa, have invented certain new and useful Improvements in Door-Operating Mechanisms; and we do declare the following to be a full, clear, and exact description of the invention, such as will enable others skilled in the art to which it appertains to make and use the same.

Our invention is an improved door operating mechanism designed more particularly for use on garage doors, the main object being to provide a mechanism of this class which will normally lock the door or doors in closed position but which will be operated to open the same by an automobile entering or leaving the garage.

Another object is to so construct the improved mechanism as to allow it to be operated manually for use on cellar doors or others mounted on horizontal hinges.

With these general objects in view, the invention resides in certain novel features of construction and in unique combinations of parts to be hereinafter fully described and claimed, the descriptive matter being supplemented by the accompanying drawings which constitute a part of this application and in which:

Figure 1 is an inner side view of a pair of hinged garage doors showing the application of the invention thereto;

Fig. 2 is a vertical section on the plane of the line 2—2 of Fig. 1;

Fig. 3 is a view similar to Fig. 1 showing one of the doors in open position; and

Fig. 4 is a sectional view through a floor and a vertically swinging door therein, showing a modified form of the door operating mechanism.

In specifically describing the construction shown in the drawings above briefly described, similar characters will be placed on corresponding parts throughout the several views and reference will be herein made to the numerous elements by their respective indices. To this end, the numeral 1 represents the door frame of a garage while the doors thereof are shown at 2, said doors be-

ing mounted upon hinges 3 for allowing them to swing outwardly as usual.

Secured to one side of the frame 1 adjacent the upper end of one of the doors, is a metal bracket 4, while carried by the opposite side of said frame in horizontal alignment with said bracket, is a bearing 5, a rock shaft 6 being mounted in said bracket 60 and bearing, said shaft lying parallel with the doors 2 and being positioned at right angles to the axes of the hinges 3.

A pinion or a segment thereof is keyed to one end of the shaft 6 as shown at 7, said pinion being in mesh with a gear segment 8 mounted on the inner end of the bracket 4, an upright rod 9 being pivotally connected at its upper end with said segment as shown, openings 10 being preferably provided for 70 allowing said rod to be moved adjacent or remote from the axis of the segment as occasion may demand. The lower end of the rod 9 is adjustably connected by a turn-buckle 11 with a second upright rod 12, the lower end of the latter being suitably connected at 13 with one of a pair of depressible tracks 14, one of these tracks extending into the garage while the other one is disposed in advance thereof. Both tracks 14 80 are hinged together as shown at 15 and a coiled spring 16 is connected with said hinge so as to normally raise the tracks 14 to the position shown in Fig. 2, from which position they are adapted to be depressed by the weight of an automobile entering or leaving the garage. This depression of the tracks 14 will so operate the segment 8 as to turn the pinion 7 and shaft 6, operating connections being provided between the latter and the doors 2 whereby these doors will now be opened.

The connections just referred to will be hereinafter specifically described, but before so doing, we deem it advisable to state that although a pair of tracks 14 have been shown for engagement by the wheels of the automobile, said tracks might well be replaced by platforms extending throughout the width of the door frame as will be readily understood.

The operating connections between the shaft 6 and doors 2 are here shown in the form of a pair of arms 17 rigidly secured at

one end to said shaft, and links 18 which are connected at their ends with the arms and doors. The arms 17 may be of any suitable construction and secured on the shaft 6 in any appropriate manner, set screws 19 being shown in the present embodiment of the invention for illustrative purposes. It is essential, however, that loose connections be provided between the links 18 and the aforesaid arms, in order that the latter and the doors may swing in different directions.

In the form of the invention shown in the drawings, blocks 20 are swiveled on the free ends of the arms 17, and the links 18 are equipped with forks 21 receiving said blocks and pivoted thereto upon axes extending transversely of the arms and links. The other ends of the links 18 are offset vertically at 22 and provided with integral balls 23 received in sockets 24, which latter are secured to the doors 2. By this construction and arrangement, all parts may move in the necessary manner as the doors are opened by the weight of an automobile or closed by the tension of the spring 16.

As clearly shown in Fig 2, the links 18 contact with the under sides of the arms 17 when the doors are closed, the offsets 22 of said links now allowing the aforesaid arms 20 to be disposed past dead center. As a result of this, the doors 2 cannot be opened until the arms are swung by their operating means.

In Fig. 4, the construction of all parts is substantially identical with that above described, but the application is different since said mechanism is to operate a pair of vertically swinging doors 2^a. Consequently, the bracket 4^a must be secured to the lower side 35 of the frame of said doors, thereby disposing the shaft 6^a beneath the same with the arms 17^a depending from said shaft and connected with the doors by links 18^a. In this application of the invention, one end of a 40 rod 9^a is connected to the segment 8^a, while the other end of said rod is pivoted to a lever 30 which rises beside the frame of the doors. Obviously, when said lever is operated, the mechanism will open the doors and 45 the weight of the latter will normally hold the same in closed position. However, if desired a spring might be employed for the last named purpose.

From the foregoing, taken in connection 50 with the accompanying drawings, the construction, manner of operation and advantages of the invention will be readily understood without requiring a more extended explanation, and although we have described the improved mechanism as applied to a garage door and a cellar door, it will be understood that it could well be used in other connections and that it could be operated by the weight of horses or horse-drawn 55 vehicles, or by the weight of a person. Fur-

thermore, although certain specific details have been shown and described for illustrative purposes, numerous changes may be made within the scope of the invention as claimed without sacrificing the main advantages thereof.

We claim:

1. The combination with a swinging door, of an operating arm therefor mounted on an axis lying parallel to the door and at 75 right angles to the door axis, said arm normally extending away from the door, a block swiveled on the free end of said arm, a link pivoted at one end to said block on an axis extending transversely of said arm and link, 80 the other end of said link being offset laterally and connected universally to the door, and means for swinging said arm.

2. The combination with a swinging door, of an operating arm therefor mounted on an 85 axis lying parallel to the door and at right angles to the door axis, said arm normally extending away from the door, a block swiveled on the free end of said arm, a link pivoted at one end to said block on an axis 90 extending transversely of said arm and link, the other end of said link being offset laterally and having a ball thereon, a socket secured to the door and receiving said ball 95 therein, and means for swinging said arm.

3. A door operating mechanism of the class described comprising an operating arm and means for swinging said arm, a block swiveled on the free end of said arm, a link pivoted at one end to said block on an axis 100 extending transversely of the arm and link, and a universal joint carried by the other end of said link for attachment to the door.

4. The combination with a door frame and a pair of swinging doors for closing 105 the same, of a rock shaft extending parallel to the frame in spaced relation with the inner side thereof and disposed at right angles to the axes of the doors, a pair of arms secured to said shaft, a pair of links 110 loosely connected at one end to the free ends of said arms and universally connected at their other ends to the doors, a bearing and a bearing bracket for supporting the opposite ends of the rock shaft, a pinion secured 115 on said rock shaft adjacent said bearing bracket, an operating segment pivoted to said bracket and meshing with said pinion, a rod pivoted at an eccentric point to said segment, and means for operating said rod. 120

5. In combination, a rock shaft adapted to be disposed parallel with the inner side of the door frame and at right angles to the axes of a pair of doors hinged to said frame, a pair of rigid arms projecting in 125 the same direction from said shaft, a pair of links connected loosely at one end with the free ends of said arms and having universal joints on their other ends for connecting them with the doors, a bearing and 130

a bearing bracket for supporting the opposite ends of the rock shaft, a pinion secured on said shaft adjacent said bracket, an operating segment pivoted to said bracket and meshing with said pinion, an operating rod pivoted at an eccentric point to said segment, and means for operating said rod.

5 In testimony whereof we have hereunto

set our hands in presence of two subscribing witnesses.
